COMPOSITION SOLE AND METHOD OF
MAKING SAME

John E. L. Ryan, Danbury, Conn.

Application May 18, 1944, Serial No. 536,171

13 Claims. (Cl. 36—59)

This invention relates to composition soles for shoes, sandals, slippers and the like as well as to the method of manufacture of such composition tread members.

More particularly the tread member, in accordance with my present invention, is constructed of heavy cord strands or rope wound about a core member of a flexible plastic material or rubber (either natural or synthetic) and wherein the rope is secured by the material of the core thereto, or even embedded therein, during the finishing steps of the process of making, thereby producing a commercial product.

An object of the invention, therefore, is to provide in such a manner, an improved rope shoe sole of good wearing quality, water proof, flexible, having a non-skid tread surface, light as compared with its thickness, of improved design, and easily adapted to many kinds of foot-wear.

Another object of the invention is to provide such a composition sole which is longitudinally flexible.

Another object of the invention is to form the heel and toe portions of such a composition sole so that they are more rigid or less flexible longitudinally as well as laterally as compared with the intermediate portion therebetween.

Another object of the invention is to construct such a composition shoe sole of an improved quality with a minimum amount of materials, particularly of rubber, and without waste, and with a reduced amount of labor as compared with any previous methods of constructing rope soles or composition rope and rubber soles of which I am aware.

Further objects and advantages of my invention will appear in the following specification wherein, in conjunction with the accompanying drawings, are specifically disclosed two highly satisfactory forms of rope soles in accordance with this invention, as illustrative thereof.

Figure 1 is a plan view of one preferred form of composition rope and rubber shoe sole in the process of construction;

Fig. 2 is a longitudinal sectional view thereof taken on line 2—2 of Fig. 1;

Fig. 3 is a plan view of the finished sole following a vulcanizing process on the sole shown in Fig. 1;

Fig. 4 is a detailed longitudinal sectional view of Fig. 3, on an enlarged scale illustrating the rearrangement of the wound rope strands incident to the vulcanization;

Fig. 5 is a plan view of modified form of the

composition rope and rubber shoe sole in the process of construction;

Fig. 6 is a plan view of the finished sole following the vulcanization process; and

Fig. 7 is a detailed longitudinal sectional view of Fig. 6 on an enlarged scale.

In general, heretofore numerous attempts have been made to construct composition rope and rubber shoe soles but, in accordance with various processes employed, an excessive amount of labor had been required and also materials, and therefore have not been entirely practical from a manufacturing standpoint. By way of example, such constructions have been made employing a fabricated mesh, and by cutting and stamping operations for obtaining finished soles, which necessitated a high percentage of waste.

Such objections are mainly overcome in a composition sole construction in accordance with the present invention, in that, as disclosed in the drawings, the rope sole is constructed entirely by a winding process of the rope, 10 or 10a, both forms illustrated, about a core, 11 or 11a, of uncured rubber formed somewhat smaller than the size of the finished composition sole resulting from the process.

Referring to Figs. 1 and 2 it will be seen that rope 10 is preferably of three cord strands, although a greater or less number of strands may be employed if desired, the rope being of any desired cross-section, such as round, square or rectangular section may be employed. If a rope of rectangular section is employed, the largest side of the section will be applied against the core 11. It is desirable that the rope should be waterproofed with a suitable solution, now on the market (as G. R. S. Cement as one example) to avoid moisture from seeping through to the upper part of the sole, as by capillarity. If the rope is not already waterproofed it may be at any time, before winding, or the finished sole can be dipped in waterproofing solution, after the core is cured or vulcanized.

Core 11 for the sole is preferably a flat sheet of uncured rubber cut to the shape of a sole, but a little smaller, so that when the rope is wound around it, the sole will be the required size. This core may be about one-quarter thickness of the sole for good results and is strong enough to give support to the rope when wound therearound and its surfaces are sticky so that the rope impinging thereagainst is held in place. While material as natural, reclaimed or synthetic rubber sheet material has been found to best meet these qualifications for the core and, therefore, is preferably

employed in carrying out this process into practice, other flexible materials having adhesive surfaces or flexible heat plastic materials adaptable thereto may be employed.

Rope 10 is wound laterally around the core 11 with the stretches or convolutions across the core closely paralleling each other, from the toe end 12 to the heel end 13 as best shown in Figs. 1 and 2. Naturally, care must be taken in the winding process not to distort the unvulcanized rubber body or flexible core 11, and in this winding process, as performed in a winding machine, a removable stiffener sheet (not shown) is placed over the rubber body and following winding process such stiffening element is removed.

The wound form is then placed in a vulcanizing molding press and during vulcanization the rubber impregnates for a distance the rope fibers and substantially fills the interstices so that, after vulcanization, in the finished sole the rubber has flowed and extends substantially to and about the edges of the mold, covering the rope at said edges, but preferably, with surfaces of the individual rope strands projecting slightly beyond the rubber at opposite faces of the sole, as generally shown in the finished sole presented in Fig. 3, to provide an anti-skid surface. Figure 4 further illustrates the manner in which the rope strands are rearranged during the vulcanizing process at which time the flow of the uncured rubber is such as to substantially cover or embed the stretches of the rope on the upper and lower surfaces of the core.

In the finished form of the composition sole shown in Figs. 3 and 4, it will be manifest that the portion intermediate the heel and toe is relatively flexible longitudinally of the sole and more rigid laterally thereof because of the double rope re-inforcement given by the upper and lower stretches X and Y of the rope. The flow of rubber to the toe and the heel portions is such as to increase the rigidity in these ends of the sole.

According to the modified form shoe sole illustrated in Figs. 5 to 7, the rope 10a is wound in a similar manner, as above described, on a core 11a composed of plies or layers 14 and 15, of a heat plastic material or rubber (preferably uncured rubber) with an intermediate stiffener layer of suitable material, preferably a single ply of cardboard, fibre-board or the like, 16, as illustrated in Figs. 5 and 7. This intermediate stiffener layer 16 not only acts as a stiffening element during the winding process but also functions to retain the rope convolutions or stretches separated following the vulcanization process as will be seen in Fig. 7.

While the vulcanization step of the process is identical with that for the sole illustrated in Fig. 3, that is, in placing the wound core in the vulcanizing molds, the process may be carried out employing less rubber. Accordingly, as illustrated in Figs. 6 and 7, the flow of rubber may only partly fill the interstices between the rope strands or stretches to a depth of one-half to three-fourths of the thickness of the rope, or even less, according to the thickness or amount of rubber in layers 14 and 15. Therefore, the surface of finished sole, inner and outer surfaces, are entirely rope surfaces as disclosed in the intermediate portion 17, between the heel and toe ends, 18 and 19, respectively.

In order that the wear surfaces of the heel and toe portions of the rope sole may be fully protected, a thin sheet or layer of the uncured rubber 18 and 19 may be placed on what will be—

the bottom surface of the rope stretches at said heel and toe end portions of the sole, in the manner shown in Fig. 5, prior to placing the sole in the vulcanizing mold. Likewise, to protect the edge portion 20 of the sole, a thin strip may be applied entirely around the perimeter of the sole, and, after vulcanization, fills the interstices thereof.

The finished sole, in accordance with Figs. 5 to 7, may be a little thicker than the form of sole illustrated in Figs. 1 to 4 since, in the former form, the upper and lower stretches X and Y of the rope convolutions are compressed to engage the intermediate cardboard or plastic layer, whereas, in the latter form the upper and lower rope stretches of the rope convolutions are compressed so as to over-lap alternately between one another. In both forms the total thickness of the soles is slightly thicker than the molds in which they are compressed and cured. When the soles are placed in their molds, the rubber or other heat plastic composition of the core softens, under heat and pressure, thus flowing to substantially fill the lateral interstices between the stretches of the rope—i. e., as in Figs. 1 and 4, flowing to the surface of the sole and embedding the rope strands therein excepting, preferably, for a slight protrusion of the rope through the rubber, or, as in Figs. 5 to 7, flowing as to only partially embed the rope strands, or conversely.

Having thus described, and shown by way of example, my improvements in soles for footwear and having set forth some of the objects and advantages thereof, others being apparent from the description and drawings, and having set forth two manners in which these improvements or inventions may be performed, it is to be understood that I do not limit myself to the precise constructions or methods herein set forth as the same may be varied in ways that fall within the scope of the appended claims.

What I claim is:

1. The process of manufacturing composition shoe sole which includes winding a rope transversely around a flat core of uncured rubber, and vulcanizing under heat and pressure said prepared rope wound core in a vulcanizing mold having a cavity of a size of the finished sole but which will compress said prepared core under said pressure so as to cause the upper and lower stretches of the rope convolutions extending laterally across the rubber core to be brought in closer proximity and embedded into the rubber, thereby producing a homogeneous article.

2. The process of manufacturing a composition shoe sole which includes winding a rope transversely around a flat core of a width smaller than the finished sole and having uncured rubber surfaces, and vulcanizing said rope wound core in a vulcanizing mold of less thickness than that of assembled sole so as to cause the rubber to flow under heat and pressure to at least partially fill the interstices between adjacent lateral stretches of the rope convolutions and adhere to the adjacent surfaces of the rope along the portions filled by the rubber when in a fluid state.

3. The process of manufacturing a composition shoe sole which comprises winding a rope transversely around a flat core of uncured rubber, covering a portion of an outer exposed surface of the rope on the core with a layer of rubber, and vulcanizing said rope wound core with said exterior layer of rubber in place in a mold of less thickness than that of the assembled sole so as

to cause the rubber to flow between the surfaces of the rope convolutions and adhere thereto, thereby maintaining them in place.

4. The process of manufacturing a composition shoe sole which consists in winding a rope transversely around a flat core of a size slightly smaller than the size of the finished sole and composed of layers of uncured rubber having a layer of semi-rigid stiffener material between the rubber layers, and vulcanizing said prepared rope wound core in a vulcanizing mold having a cavity of a size to compress said prepared core to cause the rubber to flow at least partially between said convolutions and to adhere thereto and to the surfaces of the intermediate layer thereby maintaining them in place and producing a homogeneous article.

5. A composition shoe sole comprising a core about which a rope is wound transversely thereof and embedded in the material of the core.

6. A composition shoe sole comprising a flexible heat-plastic core about which a continuous length of rope is wound transversely thereof and embedded in the material of the core.

7. A composition shoe sole comprising a vulcanized rubber core having a rope wound laterally therearound and at least partially embedded in the rubber of the core.

8. A composition shoe sole comprising a core of flexible plastic material having a continuous strand of rope closely wound transversely thereof around the core with upper and lower stretches impinging and adhering to corresponding interstices of the core, and the plastic core material substantially filling the interstices between the rope stretches and substantially embedding the surface thereof.

9. A composition shoe sole comprising a vulcanized rubber core having rope closely wound laterally around the core to form upper and lower stretches with portions extending about the edges of the core, said wound rope impinging corresponding interstices of the core, and the core rubber substantially filling the interstices between the rope stretches and adhering thereto to provide a homogeneous unitary structure.

10. A composition shoe sole comprising a vulcanized rubber core having a rope closely wound

laterally around the core to form upper and lower stretches with portions extending about the edges of the core, said wound rope impinging corresponding interstices of the core, and the core rubber substantially filling the interstices between the rope stretches and embedding the stretches and their edge portions therein, except that a portion of the stretches protrude beyond the rubber at the surface of the sole.

10 11. A composition shoe sole comprising an intermediate layer of stiffener core material, a single continuous length of rope wound around said intermediate layer of stiffener material as a separator between upper and lower stretches of the wound rope, and rubber at least partially filling the interstices between the rope stretches and adhering thereto and to the intermediate layer, whereby the rope stretches are held together and to the intermediate layer.

20 12. A composition shoe sole comprising an intermediate layer of stiffener core material, a single continuous length of rope wound around said intermediate layer of stiffener material as a separator between upper and lower stretches of the wound rope, rubber at least partially filling the interstices between the rope stretches and adhering thereto and to the intermediate layer, whereby the rope stretches are held together and to the intermediate layer, and a strip of rubber vulcanized to perimetral edge of the sole.

25 13. A composition shoe sole comprising an intermediate layer of stiffener core material, a single continuous length of rope wound around said intermediate layer of stiffener material as a separator between the upper and lower stretches of the wound rope, rubber at least partially filling the interstices between the rope stretches adjacent said core and adhering thereto and to the intermediate layer, whereby the rope stretches are held together and to the intermediate layer, and layers of rubber on the exterior surfaces of the rope at the toe and heel wear ends of the sole completely embedding the rope at the ends 40 and integrally combined with the other rubber to provide increased wear and rigidity at the ends of the sole.

JOHN E. L. RYAN.
